UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

WARP STOP MECHANISM FOR LOOMS.

Application filed February 9, 1928. Serial No. 253,025.

This invention relates to warp stop mechanism for looms whereby the loom is brought to rest on the occurrence of a warp fault.

Mechanical warp stop mechanisms as now generally understood are of two types, one in which the detector is given an oscillating or sliding movement in the general direction of the warp thread or towards and from the front of the loom, and the other, in which the detecting member is constituted as a toothed bar and is given movement transversely of the warp thread. The present invention is more particularly directed to the latter type of warp stop mechanism, and has for one of its objects to provide a simple and effective construction of warp stop mechanism wherein upon the occurrence of a warp fault the loom will not only be stopped but the location of the fault will be indicated to enable the loom attendant to piece up the broken or too slack thread.

In that type of warp stop mechanism wherein the detector is constituted as a toothed bar movable transversely of the loom in its detecting movement, it is now the usual practice to associate with such detector a stationary toothed detecting bar running parallel to the detector, so that when a warp thread breaks or becomes too slack for weaving purposes, the fallen drop wire will engage a tooth of the stationary toothed bar and also a tooth of the movable toothed bar and effect loom stoppage.

In accordance with the present invention, a toothed detecting bar having movement transversely of the loom, is given its detecting movements from an actuator, and, extending transversely of the toothed detector there is a series of stop bars which extend transversely above the detector in separated relation and divide the drop wires into groups, so that should a drop wire indicate a warp fault it will be engaged by the transversely movable detector and will be moved thereby until arrested by one of the stop bars at either side of the grouped drop wires. Such movement of the drop wire or drop wires will separate the warp threads of the group controlled by the drop wires between two adjacent stop bars and consequently locate the warp fault and effect loom stoppage when the detector is arrested.

The invention and new combination of parts will best be made clear from the following description and the accompanying

drawings of one good practical form thereof.

In the drawings:

Fig. 1 is a perspective view showing portions of a loom and a warp stop mechanism containing the present invention;

Fig. 2 is an enlarged sectional view on the line 2—2 of Fig. 1;

Fig. 3 is an enlarged detail view of a portion of the warp stop mechanism showing one of the drop wires released by a warp thread and the drop wires of the group separated to indicate the warp fault; and

Fig. 4 is an enlarged detail showing the relation of parts when a drop wire at the end of a group is released by a warp thread.

The loom frame 1 may be of usual construction and rising from each side thereof is the support 2 which is herein shown as an upwardly projecting rod for the support of the main portions of the warp stop mechanism at each side of the loom. Mounted upon each of the supports 2 is a cap piece 3 having a sleeve 4 through which passes the rod 5 to which may be secured a collar 6 having a downwardly extending flange 7 for the support of the detector or detectors, it being understood that there is such a support 7 at each side of the loom. Extending between the two supports 7 is a toothed detector 8 which may be appropriately guided in its transverse movements by suitable supporting means, which, in the present instance of the invention, consists of the transversely extending bars 9 having side flanges 10 between which the toothed detector 8 may be reciprocated transversely of the loom.

One of the supports 7 has an arm 11 (Fig. 3) on which is mounted the rock shaft 12 carrying a series of rockers 13 on which are mounted the actuators 14, and pivotally connected to each actuator is a link 15 in which engages a pin 16 on the associated toothed detector, the result being that when the actuators are given their actuating movement, the detectors will be correspondingly reciprocated in a direction transversely of the loom.

Each of the actuators 14 is provided with two lugs 17 (Fig. 3) adapted to be seated in the recesses 18 formed in their associated rockers 13, and each actuator is yieldingly connected to its rocker by a spring 19. Each of the rockers 13 has connected thereto a finger 20 pivotally mounted at 21 on the associated rocker and connected to the actuator

by a pin 22, the construction being such that should one of the actuators be restrained from movement with its rocker, its connected finger 20 will have its outer end portion depressed and act through a member 23 upon a pin 24 to effect loom stoppage.

The rock shaft 12 is given its rocking movement by suitable means, such as the arm 24* (Fig. 3) which has at the outer end a link 25 actuated by some going part of the loom as, for instance, a cam on the lower or cam shaft, which may be of usual construction. The construction thus far described is, or may be, substantially the same as that described 15 in the patent to Davis and Johnson, No. 1,538,625, dated May 19, 1925, and further description thereof would appear unnecessary.

Each of the transversely movable toothed 20 detectors has associated with it a series of drop wires 26 each of which is provided with a slot 27 in its upper portion through which passes the transversely movable toothed detector. The drop wires may be of any usual 25 well-known type but as shown in the present instance of the invention each is provided with an eye or opening 28 (Fig. 2) through which the warp threads *a* extend and by which the drop wires are normally supported during weaving.

The warp threads *a* pass from the usual 30 warp beam 29 (Fig. 1) over the whip roll 30 and over the warp supporting rods 31, of which there may be one at each side of the 35 warp stop mechanism, extending transversely of the loom, and, if desired, there may be a further supporting rod 32 located between the banks or series of drop wires, as indicated in Fig. 2. The warp supports may be sustained 40 by any usual or desired means but in the present instance of the invention, as indicated more clearly in Fig. 2, there is a slotted arm 33 through which passes a bolt 34 for securing the warp supports at each side of the loom. 45 At its lower end the slotted arm has a base portion 35 provided with suitable bearings 36 which support the warp supporting rod 31. In some instances it may be desirable to provide a central bridge for strengthening 50 the warp stop mechanism between the side frames, and this may be constituted by a plate 37 having a slot 38 for engagement with the central warp support 32, as indicated in Fig. 2, and at its upper portion suitable recesses 55 may be formed for the extension of the transversely movable detector supports 9. These details, however, may be varied within wide limits in accordance with the preference of the user. As shown in Fig. 2, the plate 37 60 may be appropriately supported from the warp supports 31 by arms 39.

In order that the toothed detectors, of which there may be any number suitable to the number of banks of drop wires, may be 65 retained in their seats in the side supports 7,

a cap piece 40 may be secured to each of the side supports 7 and extend above the end portions of the detector supports 9.

As hereinbefore indicated, an important feature of the present invention consists in 70 a series of stop bars which extend transversely above the movable detector or detectors and divide the drop wires into groups, so that should one of the drop wires of a group fail to be supported by a warp thread 75 it will drop or fall into engagement with the transversely movable toothed detector and be moved by it until the top portion of a drop wire in that group engages a stop bar, whereupon, the loom is stopped with the warp fault 80 indicated by a separation of the drop wires and warp threads supported thereby, a condition indicated in Fig. 1.

While the stop bars for the performance of 85 the function hereinbefore noted may be variously contrived, the present instance of the invention shows the stop bars carried by a stop frame which is so connected with the side supports of the stop motion that the stop frame may be moved upwardly to remove the 90 stop bars from between the drop wires.

The stop frame as indicated in the present 95 instance of the invention comprises the side rods 41 and 42, one of which is mounted in the bifurcated end portion 43 of the side supporting frame 7 and held therein by suitable means, such, for instance, as the cotter pin 44, so that the entire frame may be swung upwardly into the dotted line position, as 100 indicated in Fig. 2.

Extending between the two side rods 41 and 42 of the stop frame are the stop bars 45 which, when the stop frame is in operative position, extend transversely above the toothed detector or detectors 8 and between 105 the top portions of the drop wires, thereby dividing the drop wires into groups of suitable number. The stop bars 45 are strung upon the rods 41 and 42 and are held in separated relation by the separators 46, each of 110 which may be conveniently formed as a hollow sleeve, one of which is placed between each two stop bars, as indicated in Figs. 1 and 3.

In order that the stop frame may be properly held in its operative position with the stop bars extending above the toothed detectors, a yielding clip 47 may be appropriately provided by mounting it pivotally upon a pin 48 (Fig. 2) carried by an arm 49 secured 115 to the cap 40, one at each side of the loom and as indicated in Fig. 3. The clip 47 may be formed as a spring member, so that it may be readily engaged with or disengaged from the co-operating rod 42.

In some instances it may be desirable to provide a clip such as that already described on a central bridge or plate 37, as indicated in Fig. 1, whereby the stop frame may be effectively held in proper position with the 120 125 130

stop bars extending transversely above the toothed detectors and between the upper portions of the drop wires during normal position of the parts. When the clips 47 are 5 swung outwardly, as indicated in Fig. 2 by dotted lines, the entire stop frame may be swung from its operative position into the dotted line position of Fig. 2, thereby permitting the toothed detectors and their guiding 10 supports, if desired, to be removed from the loom with the drop wires strung thereon.

The stop bars 45 have their lower edge portions closely adjacent to the toothed detectors, as indicated in Fig. 2, and each of the stop 15 bars may be provided with slots 50.

During normal weaving operation the drop wires 26 are supported by the warp threads and the actuators 14 impart to the toothed detectors their movements transversely of the 20 loom. Should one of the warp threads break or become too slack for weaving purposes, the drop wire of the group which was supported by such thread will fall and be engaged by the transversely moving detector until a drop 25 wire of that group is moved into engagement with one of the stop bars which form the group, whereupon the toothed detector will be stopped, and, owing to the transverse movement imparted to the drop wire, the 30 warp threads will be separated, as indicated in Figs. 1 and 3, to indicate the warp fault. This condition is particularly observable when the fallen drop wire is an intermediate 35 one of its group, in which case it will be moved with the toothed detector and with it all other drop wires between it and the stop bar which is being approached by the fallen drop wire, thereby making a wide opening in the warp to readily indicate the warp fault 40 and then effect loom stoppage by arrest of the movement of the detector. Should one of the end drop wires of a group be unsupported by its warp thread, as indicated by Fig. 4, it will be engaged by the tooth of the detector 8 and 45 its upper portion, as indicated at 51, Fig. 4, will be arrested by engagement with the stop bar 45 forming that group, whereupon the fallen drop wire will have its lower portion swung laterally of the group, thereby forcing 50 the other drop wires of the adjoining group laterally, to again indicate the warp fault and effect loom stoppage by arrest of a detector.

When the stop frame is in its operative position, as indicated in Figs. 1 and 2, it may 55 conveniently be supported by the end portion of the bracket 49, as indicated in Fig. 3, but if desired other positioning means might be employed, the essential in this respect being that when the stop frame is in its operative 60 position it will be securely held thereto during normal weaving operations to thereby position the stop bars in transverse relation to and above the detector or detectors.

What is claimed is:

1. In a warp stop mechanism for looms, the combination of a series of drop wires normally supported by the warp threads during weaving, a transversely movable toothed detector, a series of fixed stop bars extending 70 transversely between the drop wires above the toothed detector and separating the drop wires into a plurality of groups transversely of the loom, and means for effecting loom stoppage when any drop wire of a group is 75 moved by the toothed detector into engagement with and is stopped in its transverse movement by a fixed stop bar on the occurrence of a warp fault.

2. In a warp stop mechanism for looms, the combination of a plurality or series of drop wires normally supported by the warp threads during weaving, a transversely movable toothed detector for each series of drop wires, 80 a series of fixed stop bars extending transversely above the toothed detectors and dividing the drop wires of each series into similar groups, and means for effecting loom stoppage when a drop wire of any group is 85 moved transversely into engagement with and is stopped in its transverse movement by a fixed stop bar and thereby arrests movement of the detector.

3. In a warp stop mechanism for looms, the combination of a series of drop wires, a 90 transversely movable detector, a series of fixed stop bars extending transversely above the detector and warp threads and dividing the drop wires into groups between the stop bars and provided with guiding recesses in 95 their lower edge for the transversely movable detector, and means for effecting loom stoppage when a drop wire is engaged by the toothed detector and arrests its movement by engagement with a fixed stop bar on the occurrence of a warp fault.

4. In a warp stop mechanism for looms, the combination of a series of drop wires normally supported by the warp threads during weaving, a transversely movable toothed detector, a stop frame having a series of stop bars extending transversely above the detector between the drop wires and dividing the drop wires and dividing the drop wires into groups above the warp threads, and means 110 for effecting loom stoppage when a drop wire of any group is moved transversely by the detector to indicate the warp fault and is stopped in its movement by one of the stop bars.

5. In a warp stop mechanism for looms, the combination of a series of drop wires normally supported by the warp threads during weaving, a transversely movable toothed detector, a stop frame having a series of fixed 115 stop bars extending transversely above the detector between the drop wires and dividing the drop wires into groups, spacers between and for separating the stop bars, and means for effecting loom stoppage when a drop wire 120 125 130

of any group is moved transversely by the detector to indicate the warp fault and is stopped in its movement by one of the stop bars.

5 6. In a warp stop mechanism for looms, the combination of a series of drop wires normally supported by the warp threads during weaving, a transversely movable toothed detector, an actuator for the detector, a stop 10 frame having a series of spaced stop bars extending transversely of the detector between the drop wires, means for supporting the stop frame for upward movement to remove the stop bars from between the drop wires, and 15 means for effecting loom stoppage when the the detector is arrested by a fallen drop wire through engagement of one of the drop wires with a stop bar.

7. In a warp stop mechanism for looms, 20 the combination of a series of drop wires, a toothed detector, an actuator for imparting movements to the detector transversely of the loom, a stop frame comprising side rods, one at each side of the drop wires, stop bars extending 25 between the side rods transversely above the detector and warp threads, means for supporting the stop frame that it and the stop bars may be turned upwardly from operative position, and means for effecting loom 30 stoppage when a fallen drop wire has been moved by the detector to locate the warp fault and then arrested by one of the stop bars.

8. In a warp stop mechanism for looms, the combination of a series of drop wires, a detector having teeth for engagement by a fallen drop wire, an actuator for moving the detector transversely of the loom and effecting movement of the fallen drop wire to locate the warp fault, a series of stop bars extending transversely between the top portions of the drop wires above the detector and warp threads and against one of which a drop wire is moved by the detector and then arrested to stop the detector, and means for effecting loom stoppage when the detector is stopped. 40

9. In a warp stop mechanism for looms, the combination of a series of drop wires, a detector having teeth for engagement by a fallen drop wire, an actuator for moving the detector transversely of the loom and effecting movement of the fallen drop wire to locate the warp fault, a stop frame having a series of spaced stop bars extending transversely above the detector between the top portions of the drop wires and mounted for upward 50 swinging movement, and means for stopping the loom when the detector is arrested by the engagement of one of the drop wires with a stop bar as the drop wire is moved with the detector. 55

In testimony whereof, I have signed my name to this specification.

HARRY A. DAVIS.
